UNITED STATES PATENT OFFICE.

ANDY ANDERSON, OF HOBART, OKLAHOMA, ASSIGNOR OF FORTY-NINE ONE-HUNDREDTHS TO GUST ELLWANGER, OF HOBART, OKLAHOMA.

ATTACHMENT FOR GRAIN-BINDERS.

1,231,690.

Specification of Letters Patent.

Patented July 3, 1917.

Application filed September 23, 1915. Serial No. 52,251.

To all whom it may concern:

Be it known that I, ANDY ANDERSON, a citizen of the United States, residing at Hobart, in the county of Kiowa and State of Oklahoma, have invented certain new and useful Improvements in Attachments for Grain-Binders; and I do declare the following to be a full, clear, and exact description of the invention, such as will enable others skilled in the art to which it appertains to make and use the same.

This invention relates to new and useful improvements in grain binders, and more particularly to an attachment for grain binders, whereby grain that has become flattened and tangled from rains or wind, may be successfully reaped without the loss of a considerable portion of the crop.

A further object of the invention is to provide a device of this character which is simple and durable in construction, inexpensive to manufacture and one that will be very efficient in operation.

With these and numerous other objects in view my invention consists of the novel features of construction, combination and arrangement of parts which will be herein referred to and more particularly pointed out in the specification and claim.

30 In the accompanying drawings:

Figure 1 is a side elevation of my attachment applied to a binder;

Fig. 2 is a central vertical longitudinal section taken on the line 2—2 of Fig. 3; and,

Fig. 3 is a plan view of a portion of the platform of the binder showing my attachment applied to the same.

In describing my invention I shall refer 40 to the drawings in which similar reference characters designate corresponding parts throughout the several views, and in which the letter B designates a binder, which is of the ordinary type having a platform 1, 45 a carrier apron 2 with the usual type of reciprocating knife 3, and sickle guards 4. This binder has mounted thereon the usual type of reel 5 which is adapted to rotate, and to operate in a manner well known to 50 those skilled in the use of these machines.

My grain lifting attachment consists of a longitudinally disposed rod 6 which has an eye 7 formed at its rear end, and is secured thereby to the bottom of the platform 1, by means of a bolt or rivet 8, as

clearly shown in Fig. 2 of the drawings. The rod 6 has its rear portion which is designated by the numeral 9 slightly bowed downward intermediate its ends, so that the same will be carried under the forward edge of the platform 1. At a point on the rod 6 which is designated by the numeral 10 where the bowed rear portion 9 of the same connects with the forward portion of the rod, is welded a socket 11 which is 60 adapted to receive the point of the sickle guard 4. The above described construction will afford a two point means of securing the rod 6 firmly and securely into engagement with the binder, so that the same will 65 not be easily displaced therefrom.

The portion of the rod that projects forwardly beyond the socket 11, and which is designated by the numeral 12 is disposed in the same horizontal plane as the platform 1, 75 and the forward extremity 13 of the said extension is curved upwardly a short distance for a purpose to be hereinafter more fully described. Extending upwardly and rearwardly from a point adjacent the 80 curved extremity 13 of the rod 6 is a grain carrier bar 14, which has its free end 15 straightened as clearly shown in Figs. 1 and 2 of the drawings. This grain carrier bar 14 is formed integral with the rod 6, and 85 is disposed in the same vertical plane therewith. The carrier bar 14 extends rearwardly to a point spaced above and adjacent to the outer edge of the apron 2 on the platform 1 of the binder.

In operation when it is desired to use my attachment on a binder, where the grain to be reaped has been flattened by rain or wind, a plurality of these attachments are placed on the binder, in laterally spaced relation to one another as clearly shown in Fig. 3 of the drawings. The best position of these attachments has been found to be every foot along the edge of the sickle guards, that is one attachment to every third 95 guard. When so positioned the attachments will project forward in front of the binder, and the upwardly curved forward extremity 100 13 of the same will be positioned a short distance from the ground, so that they will 105 engage and lift all the grain that has been beaten down and lies close to the ground. When engaged by the forward end of the attachment the grain will be carried along the same by the carrier bar 14 as the binder 110

moves forward, and consequently will be lifted upwardly until the same may be easily cut by the reciprocating knife 3, and carried to the rear by means of the reel 5. The 5 above described operation saves large quantities of grain that heretofore could not be reached by the binder. These attachments form an easy and simple means for lifting the said grain when flattened and tangled, 10 and owing to the simplicity of construction, and ease by which they may be secured and removed, will be found to form a very simple and efficient device of this character.

From the foregoing description of the 15 construction of my improved binder attachment the manner of applying the same to use and the operation thereof will be readily understood and it will be seen that I have provided a simple, inexpensive and efficient 20 means for carrying out the objects of this invention.

It is to be particularly noted that in applicant's device the downwardly bowed portion of the main bar of the attachment extends forwardly to and terminates a short 25 distance in advance of an adjacent guard finger in substantially the same horizontal plane as said finger, and that the bar itself is not recessed in any way which might tend 30 to weaken it, but that there is a strong socket member 11 with a deep socket receiving 35 the forward end of the adjacent guard finger, said socket member extending rearwardly in a horizontal plane from the bar at the forward end of the downwardly 40 bowed portion thereof, said socket member being formed as a distinct element projecting rearwardly from the bar, although integrally connected thereto by having the bowed portion of the bar extending to a 45 point slightly in front of the adjacent guard finger. By having the strong socket mem-

ber 11 projecting rearwardly in a horizontal plane from the bar right at this point and fit firmly over and around the forward extremity of the guard finger, a very strong structure is produced and one which will not be liable to break down when subjected to the comparatively hard service incidental to the actual use of an attachment of this character.

I claim as my invention:

In a binder, the combination with the platform and sickle guards thereof, of an attachment comprising a bar having a downwardly bowed rear portion rigidly secured at its rear extremity to the underside of the platform, said bowed portion extending forward underneath the guard fingers to a point slightly in advance of the forward extremities thereof and to the same horizontal plane as said fingers, the bar extending forward in a horizontal plane from the downwardly bowed portion and having its forward extremity curved upwardly, an integral carrying bar extending upwardly and rearwardly from the forward end of the first named bar, and a socket member distinct from the first named bar and integrally formed thereon at the forward end of the downwardly bowed portion thereof, said socket member extending rearwardly from the point where the forward end of the bowed portion terminates and in a horizontal plane and formed with a rearwardly opening socket receiving and entirely surrounding the forward end of the adjacent sickle guard.

In testimony whereof I have hereunto set my hand in presence of two subscribing witnesses.

ANDY ANDERSON.
